W. R. STEPANEK

COMPUTING MACHINE

Filed Jan. 20, 1926

UNITED STATES PATENT OFFICE.

WILLIAM E. STEPANEK, OF DETROIT, MICHIGAN, ASSIGNOR TO REMINGTON ACCOUNTING MACHINE CORPORATION, OF NEW YORK, N. Y., A CORPORATION OF NEW YORK.

COMPUTING MACHINE.

Application filed January 20, 1926. Serial No. 63,504.

My invention relates to combined type-writing and computing machines and it has for its principal object to provide certain improvements in the clearance proof mechanism of such machines.

To the above and other ends my invention consists in certain features of construction and combinations and arrangements of parts, all of which will be fully set forth 10 herein and particularly pointed out in the claims.

My invention, at least in part, is in the nature of an improvement on or modification of that described in the patent to Poole 15 No. 1,491,167, April 22, 1924, for calculating machine. Said patent shows a Remington accounting machine equipped with clearance proof mechanism for the cross footer, the construction being such that when the carriage steps out of that particular computing column in which the cross footer should be brought to zero the step of the carriage to sub-units position of such column trips off 20 a device which locks up the machine against further computing operation. At that same 25 step of the carriage the cross footer carriage is tripped off and jumps back to normal position. A tripping finger in the cross totalizer is so disposed and controlled that 30 if said totalizer has been brought to zero said finger will, during the jump-back of the carriage, immediately restore the locking device to its normal unlocking position, but if the cross totalizer has not been 35 cleared then the said device will remain in locking position.

There are some classes of work in which there is no definite column, the computing of a number in which should clear the cross 40 totalizer, and the Poole clearance proof mechanism, in the form shown in the patent, is therefore inapplicable to such a situation. In order to adapt the Poole mechanism to such a situation I have changed the time at which 45 the locking device is tripped off by the carriage, and have arranged so that the finger on the cross totalizer releases the lock on the leftward travel of the cross totalizer into computing position instead of on the 50 jump-back of the totalizer out of computing position.

One embodiment of my invention is illustrated in the accompanying drawings, all of which are more or less fragmentary so

as to show only those parts of the machine 55 that are necessary to an understanding of my invention.

In said drawings,

Fig. 1 is a front elevation with parts 60 broken away.

Fig. 2 is a plan view with parts in section on the line 2 of Fig. 1.

Fig. 3 is a left hand side elevation of the cross totalizer, partly broken away, with 65 some of the associated devices shown in section on line 3 of Fig. 1. Fig. 3 is on a larger scale than the other figures.

The Remington accounting machine is well known commercially and it is in its essential features fully shown and described 70 in the patent to Wahl, No. 1,270,471, June 25, 1918. It includes a Remington typewriter, of which in the present drawing there are shown conventionally only two types 10 and one of the numeral keys 11, 75 the latter connected into the computing mechanism by means of a link 12 as well as being connected to operate one of the types 10. The frame work of the computing mechanism includes a casting 13, which by 80 certain screws and brackets is secured to the top plate of the typewriter and which has fastened to it a number of vertical frame plates, of which only the extreme right-hand one 14 is shown in the drawing, this 85 plate being fastened to the end of the casting 13 by two screws. The numeral keys 11 and links 12 operate the actuator of the computing mechanism. Said actuator includes a vertical master wheel 15 and a cross master wheel 16, the former operating vertical totalizers as 17, 18, 19, and 20, and the latter a cross totalizer 21. There may be any 90 desired number of the vertical totalizers mounted on a truck which is not shown, but 95 which is connected to travel forward (in letter feed direction) and back with the typewriter carriage, so that each of the vertical totalizers defines a computing zone or column on the paper. The cross totalizer 100 21 is mounted on a cross truck 22 which by ball bearings 23, travels right and left in the part 24 of the stationary frame work. When in the leftward travel of the carriage a vertical totalizer 105 approaches the master wheel 15, a lug 25 thereon picks up the cross truck and draws it leftward through the width of an adding

column, this being done by means of a coupler bar or pickup beam 26 and locking bar 27, the former having a lug 28 which is engaged by the lug 25 on the totalizer. The bars 26 and 27 are pivoted at 30 to a bracket 31 of the cross truck 22, and means are provided whereby at the end of an adding column they are depressed so as to free them from the lug 25 and to allow the cross truck 10 to be jumped back to its right-hand position shown in the drawing, by means of a spring 32 shown in Fig. 3 but omitted in the other figures to avoid confusion.

When the cross truck makes its jump to 15 the right it is arrested by means of a bar 33 which projects rightward from said truck, striking against a lever 34 which at 35 is pivoted to the frame plate 14 and which is normally pressed slightly leftward by means of a spring 36. When the cross truck is in its right-hand position it presses this lever flat against the frame plate 14 but when the truck is drawn to the left the lever moves a short distance away from 20 said plate. This lever has articulated thereto a link 37 which is one element in a train of mechanism, the effect of which is to lock the numeral keys at all times when 25 one of the vertical totalizers is over the master wheel 15 and when the lever 34 is 30 in its right-hand position shown in the drawing. In the Poole patent above referred to this lever and lock are utilized for a clearance proof lock and the showing of 35 said lever and of the link 37 herein is intended as a conventional showing of such a lock. It will, of course, be understood that any suitable lock can be used.

The master wheel 16 normally turns in a 40 direction to cause addition in the totalizer 21. It can be reversed to cause subtraction by a plurality of means, the principal one including subtract cams 38 which may be mounted on any desired ones of the vertical 45 totalizers, and which when a totalizer so equipped is over the master wheel 15, depresses a follower roller 40 mounted on a lever arm 41 and normally pressed up as 50 shown in Fig. 1 by a spring. When this roller and lever occupy their upper positions shown, the master wheel 16 will add, and when they are depressed by one of the cams 38, said wheel will subtract.

The clearance proof mechanism described 55 in the Poole Patent No. 1,491,167 includes a feeler mechanism capable of detecting or testing whether or not the wheels of the cross totalizer 21 all stand at zero. Said 60 totalizer includes in each denomination a carrying wheel 42, an idler pinion 43 and a dial pinion 44, the last secured to one face of the numeral wheel or dial 45. The feeler 65 consists of a comb 46 pivoted in the side plates of the totalizers at 47 so that it can be pressed against the teeth of the pinions

44, said comb having one prong or tooth 70 projecting into the plane of each of said pinions. Each of said pinions has one tooth 49 thereof made shorter than the rest, and this tooth is so chosen that when the dial 75 45 shows a zero the short tooth 47 will register with the comb tooth 46 and if all of these short teeth register with said comb teeth the comb can rock forward to the position shown in Fig. 3, whereas if any one or 80 more of the dials shows some other digit than zero one or more of the pinions 44 will have a long tooth opposite the comb and said comb will be forced to occupy a 85 position somewhat rearward of that shown in Fig. 3. The comb 46 has secured to its right-hand end a bell crank 48, the rear end of which is articulated with the front end of an arm 50. The bell crank is pivoted at 51 and includes a vertical arm 52 which projects through a slot in the top casing plate of the totalizer and which constitutes a finger or tripper, whose position denotes the condition or state of the totalizer. If 90 the totalizer is clear the finger 52 can occupy its rear position shown in Fig. 3, but if the totalizer is not clear this finger will be forced to occupy a position forward of that shown.

A locking lever 53 with which the finger 95 52 co-operates is pivoted at 54 to a sheet metal bracket 55 which is secured in place by the same screws which secure the bracket 14 to the casting 13. This bracket extends 100 leftward a short distance behind said casting and supports several parts of the clearance proof mechanism besides the lever 53.

The locking lever 53 has three arms, one being a horizontal arm from which at its 105 left-hand end an ear 56 is bent off rearward and a notch in said ear embraces a depending portion 57 of the bracket plate 55 so as to guide the up and down motion of this arm of the lever. The lever 53 has also a 110 depending arm from which a lug 58 is bent off in such position that if the lever 34 were in its left-hand position and the lever 54 were rocked counter-clockwise from its normal position shown in Fig. 1, this lug would 115 press the lever 34 to its locking position the same as the cross truck does. This arm also carries a button 59 and the locking lever may be restored to its normal position, by depressing this button with the 120 finger.

The third and upstanding arm of the lever 53 is utilized to cooperate with a latch 125 60 which normally holds the locking lever in the position shown in Fig. 1. This latch is in the nature of a bell crank pivoted at 61 to the plate 55 and having a horizontal arm with a notch cut out of its free end to form a shoulder which cooperates with 130 a lug bent off from the upper arm of the lever 53 whereby said lever 53 is latched

against rocking counter-clockwise. The spring 62 is connected at one end to the up-standing arm of the lever 53 and at the other end to a depending arm of the bell 5 crank 60. This spring performs the double function of holding the latch in its latching position, and of giving the lever 53 a tendency to rock to locking position.

Means are provided to trip the latch 60 at 10 a certain point in the carriage travel. This mechanism includes a push wire 63, which at its right-hand end is guided in an ear 64 of the frame plate 55, the end of the wire being adapted to push the vertical arm of 15 the latch lever 60 rightward and thus release the latch. At its left-hand end the wire 63 is pivoted to an arm 65 of a bell crank, which is pivoted on a stud or pin 66, which is rigidly mounted in a sheet 20 metal bracket or frame piece 67, which is secured to the upper edge of the casting 13 by two screws 68 of which only one is shown. The bracket 67 has a base part lying flat on the casting 13, from which the metal is bent 25 upward to form a vertical portion 70 and thence forward to form a horizontal portion 71, and the stud 66 is riveted into this horizontal shelf or roof of the bracket from which it hangs downward. The arm 65 is 30 held in its normal left-hand position by means of a spring 72. The bell crank, besides the arm 65, includes a leftward extending arm 73 to which at 74 is pivoted a dog 75, which dog is controlled by a spring 35 76. A pin 77, projecting from the dog and striking the edge of the lever arm 73, prevents clockwise rotation of the dog in Fig. 2, but allows said dog to rock counter-clockwise. The forwardly projecting arm of the 40 dog is abrupt on its left-hand face, and is inclined on its right-hand face.

The clearance proof mechanism as thus far described may be identical with that shown and described in the Poole patent 45 hereinbefore referred to, and in the drawing it is shown in substantially the same form as in said patent.

In order to operate the dog 75 to trip the latch 60, I mount on one of the vertical totalizers a tripper or cam piece 78. This is here shown mounted on the top of the totalizer by means of screws 80 passing, through right and left slots in the trip piece to allow adjustment. The tripper preferably projects leftward from the totalizer and at its left end it has a nose 81, the pointed tip of which is adapted to strike against the dog 75 and to operate the same. In the drawing the parts are shown in that 55 position of the carriage travel where the left-hand edge of the nose 81 is just in contact with the inclined surface or edge of the dog 75. The next step of the carriage to the left will deflect this dog and, as the 60 latter cannot turn clockwise, the effect will be to rock the bell crank 65, 73 clockwise, pushing the wire 63 to the right and tripping the latch 60, and permitting the locking lever 53 to drop to its locking position. In the same step of the carriage that performs this operation the nose 81 will pass by the dog 75 and allow the bell crank 73, 65 to be immediately restored to its normal position by the spring 72. When the carriage is drawn back toward the right the 75 bell crank cannot rock any further counter-clockwise than it is shown in the drawing, but the dog 75 can rock in that direction about its pivot 74 and the nose 81 will therefore deflect the dog 75 without operating 80 the bell crank 73, 65. The Poole patent shows a tripper cam or wiper bar somewhat resembling the parts 78 and 81, but differently situated and disposed, as will be more particularly explained later on.

The means whereby the finger 52 cooperates with the lock lever 53 includes a horizontal cam plate or bar 82 secured to and spaced a short distance forward from the horizontal arm of the lever 53 by means of 90 posts 83 and screws 84. In the Poole patent there is shown a cam plate or bar somewhat similarly situated and mounted, and having at its left-hand end an inclined lower edge 85 which may, if desired, be retained 95 in the present construction. In the Poole patent when, the cross footer being clear, it jumped back to its right-hand position, this cam was struck by the top of the finger 52 and cammed upward, thus restoring the 100 lock lever to its normal position. In the Poole patent the under side of this bar to the right of the incline 85 was straight, so that under the conditions just above mentioned, when the cross footer reached its 105 normal right-hand position the finger 52 would continue underneath this straight lower edge of the bar 82 and would hold said bar and the lock lever 53 in their normal positions. In my construction, however, 110 I cut out that portion of the under edge of the bar 82 which normally stands above the finger 52 as indicated by the curved line 86 in Fig. 1, the result being that even when the cross-footer is in the clear condition the 115 finger 52 is normally entirely out of contact with the bar 82. The cut-out mentioned is so shaped as to produce an inclined edge 87 which if the cross totalizer is clear stands in the path of the forward (leftward) 120 motion of the finger 52. The construction is such that if, with the parts standing in the positions shown in the drawing, it is desired to add a number in the vertical totalizer 17 and a tabulator key is operated 125 to move the carriage leftward to the selected denomination in said totalizer, the first part of the leftward motion of the carriage will cause the nose 81 and associate parts to trip off the lock lever 53 and allow said lever 130

to drop to its locking position. When the lug 25 of the totalizer 17 engages the lug 28 of the pick-up beam 26 and has drawn the cross truck slightly to the left the 5 finger 52 engaging the incline 87 will raise the bar 82 and restore the lock lever 53 to its normal position where it will immediately be caught and retained by the latch 60. This will indicate a clear condition of the 10 totalizer. It will be perceived, however, that indication or proof of clearance is afforded by the motion of the carriage into the first computing column instead of, as in the Poole patent, by the motion of the carriage out of the last computing column. 15

The cross totalizer 21 may if desired, contain a spring, acting continuously to press the comb 46 against the pinions 44 and these totalizers are sometimes so constructed. 20 This spring is, however, omitted from the Poole patent and from the present drawing, so as to leave the pinions 44 free of any braking action due to the comb 46 at the time when said pinions are being rotated; 25 and a separate device is provided to press the comb against the pinions and to press the finger 52 rearward at the instant when that action is desired. The device used for this purpose in the present instance is a 30 modification of the one described in the Poole patent. The bar 82 has an ear bent forward from its upper edge and to said ear a lever or wiper device 88 is pivoted at 90, this device being acted on by a tension 35 spring 91, tending to rock the same clockwise in Fig. 2. The leftward extending arm of the device 88 at its free end is bent downward along its forward edge to form a vertical section, and the lower part of the 40 latter is bent rearward to form an approximately horizontal section which as seen in plan view in Fig. 2, is of inverted V shape, having a right-hand incline 92 and a left-hand incline 93. This cam section of the 45 device 88 is so disposed that when the lever 53 drops to its locking position said section is substantially horizontal. This device 88, including its cam section resembles in some respects a device employed in the Poole 50 patented mechanism; but in the present case said cam section is situated some distance nearer to the pivot 54 than in Poole, so as to adapt it to a different mode of operation, and it normally stands a little lower than 55 in Poole. In the specific instance shown in the drawing, this change in the location of the cam section has been brought about partly by moving the pivot 90 rightward and partly by bending the arm of the 60 device 88 into an S shape as shown in Fig. 1.

The cam section of the device 88 is so situated that in its right and left-hand travel the finger 52 passes to the rear of it, the 65 point of the V being a little to the right of

the incline 87 of the plate 82. If, when the cross totalizer 21 starts to move toward the left, said totalizer is clear, the incline 92 will steer the finger 52 rearward to the extent of its motion in that direction, causing 70 it to encounter the incline 87 if the bar 82 happens to occupy its depressed position and to elevate said bar. In case the cross totalizer is not clear the finger 52 will be unable to assume its rear position and it 75 will itself therefore, acting on the incline 92, force the device 88 to rock against the tension of its spring 91. Said finger 52 in that event will not engage the incline 87 and will not restore the lever 53 to its unlocking 80 position. The pressure of said spring will be communicated for the moment to the comb 46. This comb is therefore subjected to spring pressure to test the wheels for 85 clearance only at the precise instant when that pressure is needed, namely during the forward motion or travel of the cross totalizer into position for computing in one of the computing zones.

In order to illustrate one instance of the 90 utility of the present improvements the machine is shown in the drawing set up for a job of distribution work. I have shown only four vertical totalizers in order to save space on the drawing, but in most jobs of 95 the character mentioned there would be a larger number. In this work the left-hand totalizer 17 and the corresponding column on the paper will be used to write the total amount of an item, which total amount is to 100 be distributed among other columns variously classified. For example, in keeping account of sales of merchandise, a bill of goods sold to a particular customer might amount to \$100, which amount would be 105 entered in totalizer 17. This amount is to be distributed among the different columns on the paper and the different vertical totalizers 18, 19, 20 etc. according to the classifications of the goods sold. Thus, of the 110 \$100, \$40 might be for cutlery, \$50 for machinists' tools and \$10 for sheet metal. The various distribution columns on the paper and totalizers 18, 19 etc. would be designated for these various classes of merchandise and perhaps for a number of other classes. One bill of goods might be entirely 115 of one class, so that the entire amount would be added into one of the distribution totalizers and another bill might be for a half dozen different classes of merchandise and would be distributed among the various appropriate columns and totalizers. Each of these distribution totalizers is provided with 120 a subtract cam 38 so that whatever amount is entered into any one of them would be subtracted from the cross footer, whereas the first totalizer 17 is not so provided and amounts added in it will therefore be added 125 in the cross totalizer. The sum total of all 130

these distribution items should be equaled to the amount originally entered into the totalizer 17 and cross footer 21 and when the last of them is written, if the work has been correctly done, the cross totalizer will be brought to zero. It is obvious however, that the cross totalizer may be brought to zero in any one of the numerous columns on the paper except column 17. There is no single column at which the cross footer should invariably be cleared, and the clearance proof mechanism of the Poole patent is therefore not well adapted for this particular piece of work. At whatever column the cross totalizer is brought to zero or cleared it should be clear when a new amount is about to be entered in totalizer 17. It will be seen that my mechanism tests the cross totalizer for clearance as the carriage enters the first column and that it is therefore adapted perfectly for this use.

In distribution work some explanatory matter is usually written in the left part of each line of writing so that when the carriage is drawn back to the right it usually has some distance to travel leftward before the totalizer 17 reaches computing position, and the carriage is usually brought into position to compute in that totalizer by means of the tabulator mechanism. The carriage therefore may move rapidly into column 17 and for that reason I have shown the nose 81 spaced somewhat to the left of the totalizer 17 so as to trip off the locking lever 53 an appreciable instant of time before the finger 52 gets into position to strike the incline 87, this time being given so that the locking lever may have time to drop to its locking position before the finger 52 strikes it. In case no such space was left at the beginning of each line of writing but the column 17 was itself the first thing written on the paper, then this nose could be moved a suitable distance to the right of the position shown because then the carriage could not enter the computing column so rapidly.

In case a spring is put into the totalizer 21 to press the comb 46 normally against the pinions then the mechanism could, if desired be used to show clearance on the jump-back of the cross footer, the same as in the Poole patent except that the finger 52 would be drawn to its rear position by the said spring instead of by the device 88. The machine could be adapted for different classes of work by substituting for the tripping device, 78, 81 another differently disposed.

Various changes may be made in the details of construction and arrangements without departing from my invention.

What I claim as new and desire to secure by Letters Patent, is:—

1. The combination with a carriage having a forward and return movement through

a plurality of computing zones, a cross totalizer having register wheels for registering numbers in the several said zones, and a feeler device adapted to be pressed against said wheels to test them for clearance, of means acting to press said feeler device against said wheels by the forward motion of said carriage.

2. The combination with a carriage having a forward and return movement through a plurality of computing zones, a cross totalizer having register wheels for registering numbers in the several said zones, and a feeler device adapted to be pressed against said wheels to test them for clearance, of means acting to press said feeler device against said wheels by the forward motion of said carriage into the first of said zones.

3. The combination with a carriage having a travel through a plurality of computing zones, and a cross footer adapted to register numbers in the several said zones and comprising a jumping element having a forward travel and a jump-back in each of said zones, of a device set by the carriage travel to indicate non-clearance of said cross footer and means controlled by the state of said cross footer as to clear or not clear and acting during the forward travel of said jumping element to restore said indicating device in case said cross footer is clear.

4. The combination with a totalizer and a master wheel, one of said parts having a travel forward and back for each number registered in said totalizer, and a clearance proof device for said totalizer, of means whereby said clearance proof device is operated automatically by the forward travel of said part into position to register the first number of a computation.

5. The combination with a carriage having a travel through a plurality of computing zones, and a cross footer adapted to register numbers in the several said zones and comprising a jumping element having a forward travel and a jump-back in each of said zones, of a device set by the carriage travel to indicate non-clearance of said cross footer and a device in said cross footer adapted to occupy one position when the cross footer is clear and another position when said cross footer is not clear, the two said devices being adapted when the totalizer is clear to cooperate in such wise as that the first said device is restored to its clearance indicating position by the second said device during the forward travel of said jumping element into position for the registering of the number.

6. The combination with a carriage having a travel through a plurality of computing zones and a cross footer adapted to register numbers in the several said zones and comprising a jumping element having a forward travel and a jump-back in each of said

zones, of a locking lever set by the carriage in its forward travel into one of said computing zones to indicate non-clearance of said cross footer, and a clearance testing device in said cross footer adapted to restore said locking lever during the forward travel of said jumping element.

7. The combination with a carriage having a travel through a plurality of computing zones, a series of vertical totalizers, each defining one of said zones, a cross footer adapted to register numbers in the several said zones and comprising a jumping element having a forward travel and a jump back in each of said zones, of a locking lever to indicate non-clearance of said cross footer, means whereby said carriage in its forward travel into the first of said zones sets said lever to locking position, and a clearance testing device in said cross footer adapted in case said cross footer is clear to reset said lever during the forward travel of said jumping element.

8. The combination with a carriage, a series of vertical totalizers traveling with

said carriage and defining a computing zone, a cross totalizer adapted to be picked up by each of said vertical totalizers on the forward travel thereof and to jump back at the end of each computing zone, a device 20 25 53 adapted to be moved to a position to indicate non-clearance of the cross totalizer, means including a finger 52 for testing the state of said cross totalizer as to clear and not clear, means for moving the said non-clearance indicating device 53 to its non-clear indicating position during the forward travel of the carriage into a computing zone, and a spring-pressed member having an incline 92 adapted during the forward travel 40 of said cross totalizer to exert pressure on said finger 52 tending to move it to clearance position, and an incline 87 on said device 53 adapted to be engaged by said finger 52 to restore said device in case said 45 cross totalizer is clear.

Signed at Detroit, in the county of Wayne and State of Michigan, this 8th day of January A. D. 1926.

WM. R. STEPANEK.
